UNITED STATES PATENT OFFICE.

VAN BUREN LAMB, OF NEW HAVEN, CONNECTICUT, ASSIGNOR TO KEYSTONE
BRAKE SHOE COMPANY, OF NEW YORK, N. Y., A CORPORATION OF NEW
YORK.

BRAKE CONSTRUCTION.

No. 856,266.

Specification of Letters Patent.

Patented June 11, 1907.

Application filed October 28, 1905. Serial No. 284,921.

To all whom it may concern:

Be it known that I, VAN BUREN LAMB, residing at New Haven, in the county of New Haven and State of Connecticut, have invented certain new and useful Improvements in Brake Construction, of which the following is a full, clear, and exact description, such as will enable others skilled in the art to which it appertains to make and use the same.

This invention relates to brakes. One of the objects thereof is to provide efficient and practical means adapted to mount a brake-shoe upon a brake-head, irrespective of the types of either of these parts, and more especially to provide means for adapting a widely used but somewhat antiquated type of head to support shoes of the most modern and approved character.

Another object is to provide strong and simple shoe-supporting means which shall be adapted to be assembled with a minimum of effort in the most confined and inaccessible locations.

Other objects will be in part obvious and in part pointed out hereinafter.

The invention accordingly consists in the features of construction, combinations of elements and arrangement of parts which will be exemplified in the device hereinafter described; and the scope of the application of which will be indicated in the following claims.

In the accompanying drawings wherein is shown one of various possible embodiments of my invention—Figure 1 is a side elevation showing the same in operative position. Fig. 2 is a perspective showing a shoe with a part of a composite supporting-member positioned thereon and illustrating the method of assembling these parts.

Similar reference characters refer to similar parts throughout both views of the drawing.

This invention will be most readily understood if the following facts are borne in mind: Certain well known, but at present antiquated types of break-heads have found a broad application and are now in extensive use. These heads require the use of shoes having connecting means complementary to those of the head and thus require the use of relatively old and inefficient types of shoes. In order to bring into use the most modern types of brake-shoes, it has been

found necessary to discard the former types of break-heads and thus consign large and expensive equipments of this character to the scrap heap. It may also be noted at this point that after the parts of the truck and the brake rigging are assembled, the brake-shoes and heads are often positioned in the most cramped and inaccessible locations, and no renewal or repairing of these parts can be accomplished without marked inconvenience and considerable outlay of time and labor. The above and other defects are eliminated and many positive advantages attained in constructions of the nature of that hereinafter described.

Referring now to the Fig. 1 of the accompanying drawings, there is shown a brake-head 1 which, it may be assumed, is typical of certain forms of heads which have been in wide use for a considerable period of years. This head comprises the flanges 2, adapted to be secured to the brake-beam, and upon its forward surface is provided with a recess 3 and abutments 4 and 5. Upon this head is mounted a member 6, which may be termed an "intermediate head." The latter member 7 is preferably formed in two parts, having upon their rear surfaces the projecting perforated lugs 7 adapted to fit within the recess 3, within which they are secured as by the pin or key 8.

The outer ends of the component members 9 and 10, assuming that member 6 is of the composite type which best embodies certain features of my invention, take against the abutments 4 and 5 respectively and are thus held firmly in position.

The forward surface of the intermediate head is provided, with regard to the broader aspects of my invention, with means adapted to make connection with a shoe of any approved type, thus permitting the use of a modern type of shoe without the sacrifice of any portion of the equipment formerly in use, other than the shoes which are displaced. With regard to certain more specific features of my invention, I adapt the forward surfaces of the parts 9 and 10 to make connection with a shoe 11 provided upon its rear surface with an undercut tenon 12 tapered from its central portion toward each of the ends of the shoe. This member is preferably in two portions, as shown in the drawings so as to adapt the same to perform certain

functions not immediately concerned with the present invention, but if desired, the shoe may be made in a single piece. Tenon 12 is adapted to rest within corresponding mortises 13 and 14 in the forward faces of the members 9 and 10 respectively, thus mounting the shoe upon the intermediate head and through this part upon the head 1.

In order to avoid the chance of ambiguity in the meaning of certain of the claims, it may here be noted that by the term "dissimilar," as used throughout this specification and the following claims, is meant a characteristic by virtue of which the parts described are of types differing in some respect. Thus, in regard to connecting means between the intermediate head and the parts secured thereto, bringing out a dominant feature of my invention whereby I provide means for the efficient use of shoes of any desired type in connection with heads of any type with the above noted advantages.

The method of use of the above described embodiment of my invention is as follows:

Assuming that it be desired to mount the shoe 11 upon the head 1, the parts of the intermediate head are separately slipped over the tenon 12, and the lugs 7, being thus brought together are inserted in the recess 3 and secured in place by the key 8. If it be desired to use a multiple shoe, the same is mounted in a similar manner, the outer shoe being first secured to the shoe 11 by separately slipping over the tenon formed thereon, it being assumed that this shoe is identical with that shown, a part or parts provided with the mortise or recess indicated in dotted lines at 15. The intermediate head is then placed in position upon the shoe 11, as above described, and mounted upon the head 1 in the above manner.

It will thus be seen that I have provided simple and efficient means adapted to accomplish the several objects of my invention, and that this means is of the most inexpensive construction and thoroughly reliable action. The several parts are secured in place with a minimum of effort and may readily be detached or replaced in the most confined positions. The entire construction is of an essentially practical character, moreover, and is well adapted to meet the requirements of the severe conditions incident to the use of apparatus of the character of that with which this invention deals.

As many changes could be made in the above construction and many apparently widely different embodiments of my invention could be made without departing from the scope thereof, I intend that all matter contained in the above description or shown in the accompanying drawings shall be interpreted as illustrative and not in a limiting sense. I desire it also to be understood that the language used in the following claims is

intended to cover all of the generic and specific features of the invention herein described and all statements of the scope of the invention, which, as a matter of language, might be said to fall therebetween.

Certain features herein shown and described are shown, described and claimed in my Patent No. 846,481, dated March 12, 1907, and, accordingly, are not claimed herein.

Having thus described my invention, what I claim as new and desire to secure by Letters Patent, is:

1. In brake construction, in combination, a brake-head, a brake-shoe having upon its rear surface a projecting part of decreasing thickness toward its ends and provided with undercut lateral surfaces converging toward the ends of the shoe, a supporting member adapted to fit said projecting part and be connected thereby to said shoe, and dissimilar connecting means adapted to secure said member to said head.

2. In brake construction, in combination, a brake-head, a brake-shoe having upon its rear surface a projecting part provided with undercut surfaces, and a two-part supporting member, the parts of which are respectively adapted to fit the corresponding halves of said projecting part and in assembled condition to abut against one another, the abutting ends being provided with lugs adapted to co-act with lugs upon said brake-head and secure the same thereon.

3. In brake construction, in combination, a brake-head provided with a pair of forwardly extending projections, a brake-shoe provided upon its rear surface with a projecting part, and a two-part supporting member, the parts of which are adapted to fit said projecting part and the inner ends of which are each provided with a lug, said lugs being adapted with the parts in assembled condition to abut against one another and rest between the projecting portions of said head and maintain said supporting member in operative relation to said head.

4. In brake construction, in combination, a shoe, a projecting part upon the rear of said shoe, the lateral surfaces of which converge toward the ends of the shoe, and a two-part supporting member, each part of which embraces a portion of said projecting part upon said shoe.

5. In brake construction, in combination, a shoe, a projecting part upon the rear surface of said shoe having undercut lateral surfaces converging toward the ends of the shoe, and a two-part supporting member, each part of which embraces a portion of said projecting part.

6. In brake construction, in combination, a two-part shoe, each part of which is provided upon its rear surface with a projecting part the lateral surfaces of which converge

- toward the ends of the shoe, and a two-part supporting member, each part of which is adapted to embrace the projecting portion of the corresponding part of said shoe.
- 5 7. In brake construction, in combination, a brake-head having a recess in its forward surface, a brake-shoe having upon its rear surface a projecting part the lateral surfaces of which converge toward the ends of the shoe, and a two-part member, the parts of which are adapted to embrace portions of said projecting part and are provided with perforated lugs adapted to be secured within said recess in said head.
- 15 8. In brake construction, in combination, a brake-head, a brake-shoe having upon said rear surface a projecting part the lateral surfaces of which converge toward the ends of the shoe, a two-part supporting member provided with connecting means adapted to coact with said projecting part, and dissimilar connecting means adapted to secure said two-part member to said head.
- 25 9. In brake construction, in combination, a brake-head provided with a recess, a brake-shoe having upon its rear surface a projecting part the lateral surfaces of which are undercut and converge toward the ends of the shoe, an intermediate two-part member, the parts of which are adapted to embrace portions of said projecting part and are each provided with perforated lugs adapted to rest within said recess in said head, and means adapted to pass through portions of
- 35 said head and said perforated lugs and secure said two-part member upon said head.
10. In brake construction, in combination, a brake-head, a two-part brake-shoe each part of which is provided upon its surface with a projecting part the lateral surfaces of which are undercut and converge toward the ends of the shoe, a two-part supporting member adapted to embrace said projecting parts upon the parts of said shoe and be connected by the same thereto, and dissimilar connecting means between said head and the parts of said member.
- 40 11. In brake construction, in combination, a brake-head, a two-part brake-shoe each part of which is provided upon its surface with a projecting part the lateral surfaces of which are undercut and converge toward the ends of the shoe, a two-part supporting member adapted to embrace said projecting parts upon the parts of said shoe and be connected to the same thereto, and dissimilar connecting means between said head and the parts of said member, said means comprising 45 a perforated lug upon each part of said member adapted to be secured within a recess in said head.
- 50 In testimony whereof I affix my signature in the presence of two witnesses.
